UNITED STATES PATENT OFFICE.

HARRY E. HORNER, OF SYRACUSE, NEW YORK.

GARBAGE-STRAINER.

1,021,150.

Specification of Letters Patent. Patented Mar. 26, 1912.

Application filed March 8, 1911. Serial No. 613,001.

To all whom it may concern:

Be it known that I, HARRY E. HORNER, a citizen of the United States, residing at Syracuse, in the county of Onondaga and State of New York, have invented new and useful Improvements in Garbage-Strainers, of which the following is a specification.

This invention relates to garbage strainers, and more particularly to that type which is adapted to be used in kitchen sinks.

The object of the invention is the provision of a device of this character having a door or lid for covering the same which is automatically raised when a garbage receptacle is placed thereupon to dump its contents and which is automatically closed, returning the parts to normal when the receptacle is removed.

A further object of the invention is the provision of a simple, sanitary and cheaply constructed device employing a strainer member which may be readily removed for cleaning and which is continuously covered except when material is being dumped into the strainer.

A still further object of the invention is the provision of a device of this character wherein the strainer member is inclosed or substantially inclosed within a casing having an automatically operated door which is automatically closed immediately upon removal of the receptacle being dumped, so that the contents of the strainer will not draw flies and so that the odors of the contents will not escape.

Further objects of the invention will appear as the following specific description is read in connection with the accompanying drawings, which form a part of this application, and in which:

Figure 1 is a perspective view of the device. Fig. 2 is a vertical section showing the door in closed position in full lines and in open position in dotted lines. Fig. 3 is a vertical sectional view taken at right angles to that in Fig. 2. Fig. 4 is a detail top plan view with the door removed.

Referring more particularly to the drawings, 1 represents a substantially rectangular casing supported upon legs 2 and 3 which are arranged at each corner thereof. The legs 2, which are mounted at the rear of the device, are somewhat shorter than the legs 3 which are mounted at the forward portion of the casing so that the device may

be readily supported upon an inclined drain board, or the like, and still be vertical.

Secured within the casing 1 at intervals around its interior and adjacent the top thereof are suitable supporting brackets 4 upon which the reinforced flange 5 of the strainer member is adapted to rest. This strainer member comprises a tapering foraminous body 6, the upper portion of which is constructed of suitable mesh wire netting 7 and the lower portion of which is indicated at 8 and is constructed of a similar fabric, but of a smaller mesh and is soldered or otherwise secured to the part 7 and forms a continuation thereof, having a bottom 9 to support the garbage. This strainer member or receptacle is removably mounted within the casing and to facilitate removal handles 10 are secured to its upper portion and are positioned so that they may be readily grasped when the lid or cover is raised, as will hereinafter be described, and the receptacle or body 6 removed so that the contents thereof may be dumped and so that the same may be readily cleaned.

Hinged to the rear side of the casing 1 is a cover or door 11 having depending side flanges 12 which encompass the upper edge of the casing and in which suitable slots 13 are formed. The lid also has secured in its lower edge a reinforcing wire or rod 14 and extending from the front to the rear, upon the under side of the top of the cover, are reinforcing strips or bars 15 which also perform the function of wear plates, as will hereinafter appear.

Mounted upon opposite sides of the casing and extending above the top edge thereof are pivotal arms or brackets 16 which have their upper ends bent upwardly at right angles, as shown at 17, to receive the bearing sleeve 18 of a substantially rectangular operating lever 19. This lever has its sides or end portions provided with loops 20 which surround and are soldered, or otherwise secured, to the sleeves 18. The yoke portion of the frame 19 forward of the loops 20, when in normal position, is extended from its pivotal connection on an incline with respect to the top of the casing and is so positioned that when depressed by the weight of the receptacle to be dumped, as will hereinafter be described, is adapted to lie within receiving brackets 21 secured to the front of the casing. The rear end of the frame 19 is

arranged at an obtuse angle to the forward portion thereof and its ends are extended through the slots 13 and meet in the center of the cover or top and operate over the 5 wear plates 15, the casing being cut away, as shown at 22, to permit the passage of said ends and to permit their operation in the slots 13. The front of the cover is also cut away, as shown at 23, to permit the passage 10 of the same over the brackets 21 and the terminal ends of the right angular extensions 17 are turned downwardly, as shown at 24, to prevent disengagement of the sleeves 18. The bending of the terminal 15 ends is done after the sleeves have been mounted thereon.

In the operation of the device the receptacle to be dumped is placed upon the upper portion of the frame 19 so that the 20 weight thereof will depress the same, whereby it will be seated in the brackets 21. This action throws the inner end of the frame upwardly which raises the door to the position shown in dotted lines in Fig. 2. When 25 the weight of the receptacle being dumped

is removed from the frame, the weight of the door will close the same and return the frame to normal position. This frame constitutes, in effect, a bell crank lever or in other words a pair of connecting bell crank levers.

Having thus described the invention, what I claim as new is:—

In a device of the class described, a casing, a strainer receptacle mounted in the casing, a cover hinged to the casing having overhanging slotted sides, pivotal members carried by the casing, a pair of connected bell crank levers pivotally mounted upon said members and adapted to be operated by the receptacle to be dumped, said bell crank levers adapted to enter the slots and raise the door, and supports for the bell crank lever when operated.

In testimony whereof I affix my signature in presence of two witnesses.

HARRY E. HORNER.
